LIQUID CARBONATION

Carl J. Holinger, Plainfield, N. J.

Application August 3, 1940, Serial No. 350,171

3 Claims. (Cl. 261—115)

This invention relates to carbonators for charging water with carbonic acid gas to make carbonated water such as used for beverage purposes.

My copending application Serial No. 163,577, filed September 13, 1937, now Patent No. 2,217,841, discloses a carbonator having a receptacle filled with carbonic acid gas and into which water is sprayed or atomized to carbonate it. The gas is supplied to the receptacle at a predetermined pressure and the water is admitted at an appreciably higher pressure so as to effect comminution of the water as it enters the receptacle to facilitate absorption of the gas by the water. The differential pressure is maintained by utilizing the gas when it is at a relatively high pressure, say 60 pounds per square inch, to cause the water to be admitted to the receptacle at that pressure. Before the gas enters the receptacle it is stepped down in pressure to, say, 45 pounds. Thus the water enters the receptacle at a pressure which is approximately 15 pounds per square inch higher than the pressure of the gas in the receptacle.

The carbonator constituting the subject matter of this application, like that disclosed in my copending application, is especially designed for use in so-called drink-vending machines, the size of which must be maintained as small as possible. Therefore, it is important that the carbonator be small and compact and simple in construction and operation.

By maintaining the above-mentioned differential pressure between the water and the gas in a different manner than that disclosed in my copending application above referred to, I have further simplified and made still more compact the carbonator disclosed in that application.

In accordance with this invention gas is admitted to the carbonator receptacle at a predetermined pressure, say around 45-55 pounds per square inch, and the water is pumped directly to the receptacle. The pressure at which the water enters the receptacle is determined by an inlet valve having a spring which exerts a closing pressure on the valve. The water pump is automatically stopped when the carbonated water collecting in the carbonator receptacle reaches a predetermined level, and is automatically started when enough carbonated water has been withdrawn from the carbonator to bring it to a predetermined low level. The closing pressure which the spring exerts on the water inlet valve is set, preferably by adjustable means, so that even after the water pump starts, the water pressure must be built up to a predetermined amount before the water will enter the carbonator. Prefer-

ably the tension of the spring is so adjusted that the water entering the carbonator receptacle will always be at a pressure which is approximately 15 pounds per square inch higher than the pressure of the gas within the receptacle. Thus, if the gas entering the carbonator is at a pressure of 45-55 pounds per square inch as above stated, the water will always enter the carbonator at a pressure of about 60-70 pounds per square inch, thus insuring that the water will be finely atomized or comminuted as it passes by the valve and enters the carbonator receptacle.

The accompanying drawing shows in vertical section a carbonator constructed in accordance with the invention and capable of carrying out the improved method.

Referring to the drawing, the carbonator comprises a receptacle having side walls 1, a bottom 2, and a top plate 3 preferably welded to the side walls 1. Carbonic acid gas under pressure is admitted to the carbonator through a pipe 4 threaded into the top plate 3. A commercial tank of carbonic acid gas (not shown) may constitute the source of supply of the gas and a pressure-reducing valve of the well-known type may be employed to reduce the gas pressure to around 45-55 pounds before it enters the carbonator. A safety valve 5 is mounted on the carbonator to prevent the pressure within the receptacle from rising above a predetermined maximum.

Water is pumped from a tank 6 in the drink-vending machine to the carbonator receptacle by means of a pump 7 operated by an electric motor 8. The delivery pipe 9 of the pump is detachably connected to a nozzle 10 which is removably screwed into the cover 3 as shown at 11. The nozzle 10 has a central bore 12 which conducts the water into the interior of the carbonator receptacle. The water is discharged from the nozzle through lateral openings 13 provided in the side walls of the nozzle. The lower edge of the bore 12 forms a valve seat, as shown at 14, against which a ball valve 15 is adapted to seat. The lateral openings 13 are located immediately below this valve seat. The ball valve 15 is yieldingly urged toward its seat by a plunger 16 and a coil spring 17 which is interposed between a shoulder 18 on the plunger and an adjustable sleeve 19 threaded into the lower end of the nozzle as shown at 20. The sleeve 19 is locked in position by means of a lock nut 21. When the nozzle is removed from the carbonator, the seating pressure which the spring 17 exerts on the ball valve may be regulated by loosening the lock nut 21 and then adjusting the position of the sleeve 19 as by

means of a screw driver inserted in a notch 22 at the lower end of the sleeve. When the proper adjustment is made, the lock nut 21 is tightened to lock the sleeve in its adjusted position.

The nozzle is surrounded by a tubular casing 23 which depends from the cover 3 of the carbonator receptacle and constitutes a mixing chamber. Near its upper end the casing 23 is provided with a series of openings 24, and near its mid portion it is provided with another series of openings 25. The casing 23 is closed at its lower end by a plate 26 to which is fastened a tube 27 which projects upwardly into the casing preferably to a point just above the openings 25.

Carbonated water collects in the lower part of the receptacle as indicated at 28 and a certain amount is withdrawn through an outlet 34 every time a coin is inserted into the machine. A float 29 rises and falls with the level of the carbonated water 28 and operates a rod 30 to which is fastened a pair of adjustable collars 31. An electric switch 32 is provided with an arm 33 which is actuated by the collars 31 as the float 29 rises and falls. The collars 31 are so adjusted on the rod 30 that when the level of the carbonated water 28 in the receptacle reaches a predetermined low level, the switch arm 33 is moved downwardly by the upper collar 31 to close an electric circuit to the motor 8 and thereby start the pump 7 to supply water to the carbonator receptacle. When the carbonated water 28 rises to a predetermined high level, the lower collar 31 swings the switch arm 33 upwardly and thereby breaks the electric circuit to the motor 8 and stops the supply of water to the carbonator receptacle.

Assuming that the supply of carbonic acid gas has been turned on and that the apparatus is otherwise ready for operation, then the first step in a cycle of operations is the withdrawal of some of the carbonated water 28 from the receptacle. When the carbonator is used in a drink-vending machine, this would occur when a coin is inserted in the slot. The portion of carbonated water withdrawn from the carbonator would be automatically mixed with a quantity of syrup to make the beverage. When the level of the carbonated water drops a predetermined amount, the switch 32 is operated by the float 29 to start the electric motor and thereby pump water through the pipe 9 into the carbonator receptacle. The tension of the spring 17 has been previously set so that water will not enter the carbonator receptacle unless it is at a certain appreciable pressure above the pressure of the gas within the receptacle. Preferably the adjustment is such that if the gas pressure within the receptacle is, say 45 pounds per square inch, the pressure of the water must be about 15 pounds higher, or around 60 pounds per square inch before the ball valve 15 will allow it to enter the carbonator. When the water has attained this pressure, the ball valve 15 will open far enough to allow the water to issue in comminuted or atomized form past the ball valve and through the openings 13 in the side walls of the nozzle. The water will strike the interior surface of the cylindrical casing 23 and will be deflected downwardly as indicated by the dotted lines. Some of the gas within the carbonator receptacle will enter the interior of the casing 23 through the openings 24 and 25 and through the interior of the tube 27 and will come in contact with, and be absorbed by, the water as it is sprayed into the casing 23. The carbonated water will collect in an annular pocket

formed by the tube 27 and the lower part of the casing 23 and will overflow from this pocket through the openings 25 and be collected in the lower part of the carbonator receptacle as indicated at 28. When the level of the carbonated water 28 has risen a predetermined amount the electric switch 32 is operated by the float 29 to break the electric circuit to the motor 8 and thereby stop the supply of water to the carbonator.

It will be noted that no matter what the pressure of the gas within the carbonator receptacle happens to be, this pressure, acting as it does on the ball valve 15, will be added to the pressure exerted on the valve by the spring 17, so that the water will always be admitted to the receptacle at a pressure which exceeds by a predetermined amount the pressure of the gas within the receptacle, this differential in pressure depending upon the pressure which the spring 17 is made to exert upon the ball valve 15. Inasmuch as the ball valve always causes the water to be admitted to the receptacle at an appreciably higher pressure than the pressure of the gas within the carbonator, water entering the casing 23 will be finely comminuted or atomized and sufficient turbulence will be brought about to facilitate absorption of the carbonic acid gas by the water.

It will now be seen that the apparatus is compact and simple in construction and is well suited for use in a drink-vending machine.

I claim:

1. A carbonator comprising a receptacle having a mixing chamber therein provided with a pocket to collect water sprayed into the chamber and with openings therein through which gas may enter said chamber from said receptacle and through which carbonated water overflowing said pocket may enter the receptacle, said pocket being so placed that spray entering the mixing chamber is caused to hit water in said pocket with sufficient force to cause vigorous agitation, means for supplying gas to said receptacle at a predetermined pressure, a restricted water inlet located in the receptacle and within said mixing chamber in close proximity to the walls of said chamber, a valve at the extremity of said water inlet for controlling the passage of water therethrough into the mixing chamber, mechanical yielding means adjusted to exert on the valve a closing pressure such that water will be admitted into said mixing chamber only when the pressure differential between the water at the inlet and gas in the receptacle will cause the water issuing from the valve controlled inlet to be atomized sufficiently to facilitate absorption of the gas in the chamber by the water, means controlled by the rise and fall of the carbonated water in the receptacle to lower and raise the water pressure at said water inlet, and means for withdrawing carbonated water from the receptacle.

2. A carbonator comprising a receptacle having a cylindrical mixing chamber therein provided with an annular pocket to collect water sprayed into said chamber and provided with openings through which gas may enter said chamber from said receptacle and through which carbonated water can leave said mixing chamber and enter the receptacle, means for supplying gas to such receptacle at a predetermined pressure, a restricted water inlet located in the receptacle and within said mixing chamber in close

proximity to the walls of said mixing chamber, a ball valve within said chamber at said inlet for controlling the passage of water therethrough into the mixing chamber, mechanical yielding means adjusted to exert on the valve a closing pressure at least fifteen pounds greater than the pressure of the gas in the receptacle, means controlled by the rise and fall of the carbonated water in the receptacle to lower and raise the water pressure at said water inlet, and means for withdrawing carbonated water from the receptacle.

3. A carbonator comprising a receptacle having a mixing chamber therein in communication with the interior of the receptacle, means for supplying gas to said receptacle at a predetermined pressure, a water inlet located in the receptacle and within said mixing chamber in close proximity to the walls of said chamber, a

5 pocket in said chamber to catch the water entering the chamber through said water inlet, said pocket being so positioned as to cause the water entering the chamber to strike any water in the pocket with sufficient force to cause agitation, a valve at said inlet for controlling the passage of water through the mixing chamber, mechanical means adjusted to exert on the valve a closing pressure such that water admitted into said 10 mixing chamber will be subject to pressure drop sufficient to cause water issuing from the valve controlled inlet to be atomized sufficiently to facilitate absorption of the gas in the chamber by the water, means controlled by the rise and fall of the carbonated water in the receptacle to lower and raise the water pressure at said water inlet and means for withdrawing carbonated water from the receptacle.
